(57) **CLAIM**

The ornamental design for a remote control, as shown and described.

DESCRIPTION

FIG. 1 is a perspective view of a remote control showing our new design;

FIG. 2 is a front view thereof;

FIG. 3 is a rear view thereof;

FIG. 4 is a side view thereof, the opposite side view being a mirror image;

FIG. 5 is a top side view thereof; and,

FIG. 6 is a bottom view thereof.

The dash-dash broken lines depict portions of the remote control that form no part of the claimed design. The dash-dot-dash broken lines defines a boundary of the claimed design and are not itself part of the claimed design.
